UNITED STATES PATENT OFFICE.

LEWIS FERRY MOODY, OF PHILADELPHIA, PENNSYLVANIA.

ROTARY HYDRAULIC PUMP.

1,321,538.

Specification of Letters Patent. Patented Nov. 11, 1919.

Application filed May 8, 1918. Serial No. 233,210.

To all whom it may concern.:

Be it known that I, LEWIS FERRY MOODY, a citizen of the United States, residing at Germantown, Philadelphia, in the county 5 of Philadelphia and State of Pennsylvania, have invented certain new and useful Improvements in Rotary Hydraulic Pumps, of which the following is a specification.

One of the objects of my invention is to 10 provide a new and improved pump of the type in which a rotary impeller imparts velocity energy to the fluid to overcome the head on the delivery side of the pump, and an important feature of the invention relates 15 to the attainment of high specific speeds—that is, high rotational speeds for pumps discharging large quantities of fluid under low net heads—with a minimum sacrifice of efficiency. Among the advantages which 20 may be realized are the reduction in size and weight of pumps and the possibility of adapting pumps for low net heads when directly driven by steam turbines, electric motors, or other high speed motors. Such 25 pumps may be used advantageously as circulating pumps for condenser water, particularly in marine service; and as drainage and irrigation pumps. Owing to its simplicity of construction and small size, my 30 pump is well suited to manufacture in standard sizes, from standard patterns.

In order to preserve good efficiency in pumps handling large quantities of water under low heads it is necessary to avoid all 35 unnecessary sources of energy loss, not only in the impeller but in the approach and discharge passages. In order to keep the dimensions of the pump within economical limits, it is necessary to employ velocities 40 in the piping and pump passages which are high in comparison with the net head produced by the pump. In order to conduct the water with such velocities to, through and away from the pump with minimum 45 loss of head, it is essential to avoid unnecessary elbows or curves in the passages and to provide against sudden changes of velocity either in magnitude or direction. In one aspect of my invention it comprises 50 means for directing the water entering the pump into a converging spiral path without conducting it around an elbow, and after it has been acted upon by the impeller, means for conducting it in a gradually ex- 55 panding spiral path without imposing a sudden change of direction at the point of

discharge from the impeller (where the velocity is very high compared to the net head) and without turning the water through an elbow after it has traversed the 60 spiral.

Therefore, in my pump, the only curvature in the path of the water from its flow in the admission pipe to its flow in the discharge pipe is the curvature of the spiral 65 path which each particle traverses in passing through the pump. The water may enter the pump in a pipe coaxial with the impeller and be gradually set into rotation by spiral guide vanes, so that each water particle follows a helical path of gradually decreasing pitch (the radius of the helix also decreasing somewhat); or when the arrangement of piping so requires, the water may enter the pump in a pipe tangent to 70 a spiral admission chamber which conducts the water circumferentially around the entrance space of the impeller and delivers it to the impeller with the same motion of rotation as the first method. After leaving the impeller, in which the motion of the water is substantially helical, it continues with a spiral motion in an annular passage between two conical walls, the path 75 of the particles now receding slightly from the impeller axis. The water particles are then collected in a spiral discharge chamber 80 which develops both axially and radially with respect to the impeller axis and finally discharges tangentially into the discharge 85 pipe. The word spiral is here used in the general sense of a helix of varying radius; that is, a space curve, not a spiral contained in a plane. In particular, the discharge 90 casing in its portion nearest the impeller 95 receives water which has a motion compounded of a rotation and an axial motion, with also a slight radial component of much less magnitude than the other components. The discharge casing therefore develops in 100 this portion in a substantially helical form. Since in this pump extremely high velocities of flow are employed, it is important for good efficiency to reduce the high 105 velocity of discharge from the impeller at a very gradual rate, and without any abrupt changes in direction or magnitude of this velocity, a consideration which is more important in this part of the pump than in any other. It is therefore an essential part 110 of this invention that there shall be no abrupt turning of the discharge from the

impeller (between its points of leaving the impeller and entering the velocity-reducing spiral casing) into a plane normal to the impeller axis, which has been a common 5 method; nor a turning into the axial direction, as is done in some pumps, by means of "diffusion" vanes. In this pump the walls of the spiral discharge casing develop in the natural whirling direction of the 10 water entering the casing, and terminate in a pipe placed tangentially to the spiral.

The pump consists of the following elements:

1. An admission chamber comprising a 15 passage or passages of spiral form discharging the water with a velocity compounded of a motion substantially parallel to the impeller axis and a rotation about that axis.

In order that the magnitude of this velocity may be as great as possible, the pump is to be placed at the lowest feasible elevation with respect to the elevation corresponding to the pressure of the supply water; the initial head so obtained (including 20 the pressure of the atmosphere) being utilized to set up a velocity having a value which is large in comparison with the net head produced by the pump.

By utilizing the head at entrance to the 30 pump to produce a velocity of rotation in the water which is nearly as great as the rotary speed of the impeller, it is evident that the relative velocity between the impeller vanes and the water may be made moderate.

2. An impeller of substantially "axial-flow" type, or approximating in general type the marine screw-propeller, acting upon a body of water which has already been set into rotation in the admission chamber. The axial-flow, or "screw" type, of impeller is adopted to permit large quantities of water to pass through an impeller of minimum diameter with the least possible change in direction of flow. The water enters and leaves 45 the impeller at nearly the same distance from the impeller axis, there being little of the centrifugal action upon which centrifugal pumps depend for producing head. Indeed for extremely high speeds the impeller can be made slightly inward-flow in order still further to reduce the net head produced by the pump, permitting the effective head to be partially offset by a slight amount of opposing centrifugal force in the 50 impeller. The impeller vanes are not formed as helicoidal surfaces, but are designed to increase the whirl of the water passing through the impeller.

3. An annular chamber bounded by substantially conical walls, in which the water leaving the impeller can rotate in a solid body before entering the discharge casing. The conical walls are arranged to give a gradual increase of area and consequent reduction of velocity from the impeller to the 65

discharge casing. The annular form of this chamber permits the water to continue in spiral paths of flow from the impeller to the discharge casing.

4. A discharge casing, adapted to receive 70 the water from the annular chamber in its natural whirling direction and to conduct it in a spiral to a tangent discharge pipe. The spiral is wrapped around the circumference of the annular chamber, and the cross-sectional area of the passage enlarges as it progresses around the circumference sufficiently not only to accommodate the increments of flow thus collected, but also continuously and gradually to reduce the velocity throughout the spiral. The tangent discharge pipe may also be gradually tapered to continue the enlargement of area and reduction of velocity. The casing so formed serves to convert the large velocity- 80 head of the water discharged from the impeller into pressure head at discharge from the pump. The largely helical form given to the spiral casing avoids undue losses of energy and permits the dimensions and 85 weight to be reduced to a minimum.

The use of a single passage wrapped completely around the circumference rather than a large number of diffusion vanes such as are sometimes employed at this point, 95 makes it possible to provide a long passage having a sufficiently gradual increase in area and with minimum curvature of path, and avoids the large surface friction and impact losses caused by a number of small passages. 100

The specific embodiments illustrated in the drawings will now be described:

Figure 1 is an axial section of one embodiment of my improved pump, with the points of the impeller vanes brought along their 105 respective circumferences into the plane of the section; this feature of the drawing is also found in Figs. 3, 5, 7 and 9.

Fig. 1^a is a cross section taken on the line 1^a of Fig. 1.

Fig. 2 is a top plan view of another embodiment of the invention.

Fig. 3 is an axial section of the same.

Fig. 4 is an end elevation of the same.

Fig. 5 is an axial section of another form 115 in which the inventive idea may be embodied.

Fig. 6 is an end elevation of the same.

Fig. 7 is an axial section of still another modification.

Fig. 8 is an elevation of an impeller which may be used in connection with embodiments of my invention.

Fig. 9 is an axial section of the same impeller.

Figs. 10 and 11 are certain developed sections of the impeller vanes as will be explained more fully hereinafter.

Fig. 12 is a diagram to be referred to in a discussion which follows.

110

120

125

130

Fig. 13 is a perspective view of an impeller having four vanes and designed according to the same principles as the six vane impeller of Figs. 8 to 11.

Referring to the form of the invention disclosed in Figs. 1 and 1^a, the pump casing is in two parts, the inflow portion being on the left and the outflow portion on the right. The inflow part of the casing has an outer wall 21 and an inner wall 22 with the annular converging entrance chamber 23 between them. Within this entrance chamber 23 are the guide vanes 24 helically inclined around the pump axis. These guide vanes 24 also serve as structural supports between the outer wall 21 and the inner wall 22 which carries the shaft bearing 37. The inflow casing member has the flange 25 connected to the registering flange 26 of the outflow casing member, which comprises the outer wall 27 and the inner wall 28 inclosing the discharge space 29 and conduit 35 between them. The discharge chamber 35 is of volute form. The walls 27 and 28 are defined by surfaces of revolution receding and flaring more and more toward perpendicularity to the axis. Between these walls 27 and 28 is the wall 32—34 which recedes gradually from the runner for points taken successively around the axis. Thus at 30 this wall is shown comparatively close to the runner, and it extends thence around the axis 90° in the direction indicated by the arrow 20, where the wall reaches a position not shown in the drawing, but which corresponds to the dotted line 31; at 180°, the wall appears at 32 (corresponding to the dotted line 32'); at 270°, the wall reaches a position corresponding to the dotted line 33; and at 360°, it appears designated by the reference number 34. Comprised within these walls 27, 28 and 32—34, is the expanding volute discharge conduit 35, which leads into the tangent discharge pipe 44. The shaft 38 turns in the bearings 36 and 37 and carries a hub 39 with the impeller vanes 40 projecting radially therefrom. The space between the inflow guide vanes 24 and the impeller vanes 40 is designated 41. The arrow 42—43 indicates the course of the water flowing through the pump. This arrow is shown short dotted where it goes behind the parts appearing in the figure and dashed where its course is not thus concealed.

The impeller 39—40 is driven by a source of mechanical power to rotate in the direction of the arrow 20. Water flows into the entrance chamber 23 under a certain head from the supply source. The entrance conduit 23 converges and the velocity of the water increases as it approaches the runner. The helically inclined vanes 24 guide the water with increased velocity in a whirling direction into space 41 as indicated by the dotted and dashed arrow 42—43. The im-

peller is rotated in the same direction under a torque such that the water is caught from the space 41 and its energy of whirl increased and it is delivered with this increased whirling energy to the space 29 where it goes on in its natural whirling direction in the expanding conduit 35 which decreases the velocity and thus absorbs the kinetic energy at 29 converting it into the potential energy of static head in the outflow conduit 44. As shown by the arrow 42—43, the water follows a converging spiral path in the entrance chamber to the impeller in which it has a substantially helical motion, and then follows an expanding spiral path from the impeller to its discharge from the spiral casing.

Referring to Figs. 2, 3 and 4, the pump is shown with its shaft 38 coupled at 47 to an electric motor 48. The pump support 46 and the motor 48 both stand on the base 45. The reference numbers have been applied in correspondence with Figs. 1 and 1^a, but the following features of the modification of Figs. 2, 3 and 4 may be specially noticed at this point. The inflow conduit 21 is convergent to increase the velocity of approach to the impeller, and the inflow guide vanes 24 all spring from a central core 22'. The impeller is overhung beyond the bearing 36. Whereas in Fig. 1, the flow at the impeller is slightly convergent, in Fig. 3 it is divergent. The water flows to the pump along the axis and leaves it in direction at a right angle to the axis. The spiral discharge conduit develops along a conical surface having straight elements, that is, the development is in a diagonal direction from the impeller to the discharge.

Referring to Figs. 5 and 6, the water flows to the pump in a direction at a right angle to the axis and leaves it in a direction at a right angle to the axis. The inflow conduit is a contracting volute 23', which delivers the water with a gradually increased whirl velocity to the impeller vanes 40, at which point an additional velocity is impressed by the power delivered through the impeller and then this velocity is absorbed in the expanding volute conduit 35 and converted into the potential energy of static head.

Referring to Fig. 7, the vanes 24 in the narrowing passage 23 direct the inflow water 49 with increasing whirling velocity to the impeller 39—40, whence it flows with a decreasing whirl in the annular diffuser 35' and discharges into the body of water 50, with a free level at 51. The stay vanes 52 are inclined so as to be edge-wise to the direction of flow. The guide vanes 24 also perform the function of stay vanes. It will be seen that the parts associated with wall 28 are supported by the stay vanes 52 on wall 27, that through flanges 26 and 25 the wall 27 rests on wall 21, and that the vanes 23

support all the said elements on the bottom wall 22.

Figs. 8 to 11 illustrate a suitable form for the impeller vanes by which they may be conveniently designed and manufactured.

- Fig. 10 represents the developed section made in the vane 40 by a conical surface having the axis 10-12 and the element 10-10'; similarly Fig. 11 represents the developed section of the vane 40 made by a conical surface having the axis 10-12 and the element 11-11'. The boundary of each section is a closed curve. These two curves serve as directrices for the vane surfaces. 10
- 15 Let any meridian plane intersect these two directrices on the same side and let a straight line in that plane touch both directrices; it will be an element of the surface of the vane 40; and the whole surface of the vane 40 20
- 25 will be swept out by a line in a revolving meridian plane, which always touches both these directrices.

By making the pump single instead of double or "twin", it is possible to realize the advantages of greater simplicity of water passages and piping, and to avoid the necessity of conducting the water to or from the impeller through elbows or pipe bends. Such elbows in addition to the losses within them already mentioned cause an unequal distribution of velocities across the entrance and discharge spaces of the impeller; so that the velocities are unsymmetrically distributed around the impeller axis, resulting in serious losses. 30

The necessity of providing a single-suction pump with a thrust bearing is not objectionable since excellent types of thrust bearing are available and may be applied 40 without difficulty. Methods of relieving the unbalanced water pressure on the impeller similar to that shown on Fig. 7 may be used.

The pump may be adapted to a great variety of arrangements of supply and discharge piping. For instance, the supply may enter in a direction co-axial with the propeller shaft and the discharge pipe may be arranged with its axis in a plane perpendicular to the shaft axis. Thus, the pump 45 may receive the water horizontally and discharge it either vertically or horizontally at right angles to the direction of supply. Another arrangement comprises the use of a volute entrance casing, as shown in Figs. 50 5 and 6, which, in combination with the discharge casing already described, permits the entrance and discharge pipes to be placed in any desired directions in parallel planes. Directions of the supply and discharge pipes 55 are inclined at small angles with respect to planes normal to the pump shaft are also readily obtainable by inclining these pipes at approximately the natural helical angles of the spirals, and are consistent with well 60 formed water passages.

For pumps discharging directly into open tanks rather than into closed pipes, the recovery of the whirling velocity of discharge from the impeller may be accomplished entirely in the annular diffusion chamber 70 formed between two curved conical walls, such as shown in Fig. 7, and it will in this case be possible to omit the spiral discharge casing. The paths of the water particles will be spirals and the action will be similar to that already described. Instead, however, of collecting all the water particles in a single pipe, the discharge will be distributed uniformly over an annular discharge opening around the pump axis. 75 80

In the design of the spiral discharge casing and of the annular transition space, in addition to providing for gradual reduction of the whirl component of velocity, it is also essential to provide against sudden changes, either in direction or magnitude, of the meridian component of velocity. For this reason, in any meridian section of the discharge casing (a meridian section is a section containing the impeller axis,) the 90 width of the section measured normally to the meridian components of flow, should vary gradually; and the walls of the passage should have smoothly curved contours; this may be understood by referring to 95 Fig. 1.

The development of the spiral may begin in the axial direction which if continued, would produce a helix and may then gradually enlarge radially as shown in Fig. 1, 100 or the development may proceed in a diagonal direction, as in Fig. 3.

In order to set forth with more definiteness some of the elementary factors entering into the operation of my pump, the following discussion is given. Referring to Fig. 12, the pump 13, driven by the motor 48, receives water from the tank 55 through the pipe 56 and discharges it through the pipe 44 into the tank 59. The water enters 110 the pump under the head due to the height h_1 of the surface of the supply water above the pump and to the atmospheric pressure acting thereon, represented by the arrows 58, and is discharged from the pump against 115 the head due to the height h_2 of the water surface in the delivery tank and to the atmospheric pressure represented by the arrows 52. To enable the pump to utilize to the extent contemplated in this invention 120 the advantages inherent in its construction and method of operation, it is to be located at such an elevation that the initial head, (h_1 plus the atmospheric head) will be large compared to the net head h against which 125 the pump is working.

When so located, the pump receives water having potential energy corresponding to the initial head, and by the conversion of a large part of this energy into the kinetic 130

form at entrance to the impeller, corresponding velocities may be obtained for the water. The velocity of the water in the pump is consequently limited only by the initial head 5 available, and has no relation to the net head produced by the pump. By directing this velocity at the impeller entrance so that it is inclined toward a tangential direction with respect to the impeller axis, the water is 10 made to enter the impeller with a whirling motion of high velocity. Without increasing the relative velocity between the impeller and water, the rotational speed of the impeller can now be increased by the amount of the 15 velocity of the whirl of the water, and the impeller can therefore be run at speeds entirely out of proportion to the net head against which the pump is acting.

By so inclining the direction of motion 20 of the water within the pump that it contains a considerable axial component of velocity as well as the tangential component, small water passages can be obtained and an impeller of small diameter can be used, conditions which are also consistent with small 25 pump dimensions, light weight and high speed. While Fig. 12 shows the elevation of the surface of the supply water higher than that of the pump, it would be possible, in cases where the net head h is sufficiently low, 30 to obtain the requisite initial head from the atmospheric pressure alone, and the water surface in tank 55 might in some cases be lower than the pump within limits.

35 The relations above described can be formulated as follows:—Letting

c_1 represent the absolute velocity of the water at entrance to the impeller, in feet per second;

40 p_1 represent the absolute pressure at entrance to impeller in pounds per square inch;

P_a represent the atmospheric pressure, in pounds per square inch;

45 h_L represent the head lost by the water due to friction, etc., in passing from tank 55 to point of entrance to impeller, in feet;

50 h_1 represent the elevation of the supply water above the pump in feet; and

g represent the acceleration of gravity, in $\frac{\text{ft.}}{\text{sec.}^2}$.

55 we have the following equation:—

$$h_1 + \frac{P_a}{0.433} - h_L = \frac{P_1}{0.433} + \frac{C_1^2}{2g}$$

Since P_1 cannot be less than the vapor 60 pressure of water corresponding to its temperature, (at usual temperatures about $1\frac{1}{2}$ pounds per square inch,) without breaking the continuity of liquid in the pipe, and in practice must be kept well above this limit, 65 the formula shows how the velocity C_1 which

can be employed at entrance to the impeller is limited by the height h_1 .

A similar equation can be written for the discharge side of the pump, namely

$$\frac{p_2}{0.433} + \frac{C_2^2}{2g} - h_L = h_2 + \frac{P_a}{0.433}$$

in which p_2 represents the pressure at discharge from the impeller C_2 the velocity at this point, h_L the total losses of head from 75 the impeller discharge to the tank 59; and h_2 the elevation of the water in the discharge tank. The pressure p_2 must be kept well above the minimum limit mentioned above 80 for p_1 .

A further equation will now be stated giving the relation between the circumferential components of the velocities C_1 and C_2 . Representing by C_{u_1} the circumferential or 85 whirl component of the velocity C_1 , and by C_{u_2} the corresponding whirl component of the velocity C_2 , and by u_1 and u_2 the peripheral velocities of the points of entrance and discharge of the impeller vanes, we have: 90

$$u_2 C_{u_2} - u_1 C_{u_1} = \frac{gh_e}{e}$$

Here h_e represents the effective head produced by the pump, or the difference in 95 elevation h of the water surfaces in the tanks 59 and 53 minus the losses of head external to the pump, that is, in the entrance and discharge pipes. e represents the hydraulic efficiency of the pump.

By turning the entrance velocity C_1 into an oblique direction as described so that the component C_{u_1} has a high value, and by giving a slightly greater value to C_{u_2} (u_1 and u_2 being nearly equal in an impeller of 105 the axial-flow type as here proposed) it is seen that while C_{u_2} and C_{u_1} may possess large values compared to the head, the effective head can be kept small; and u_1 and u_2 may be large, corresponding to high rotational speeds of the impeller. That is, each of the terms $u_2 C_{u_2}$ and $u_1 C_{u_1}$ may be large, but their difference is small.

Viewed in another aspect, this invention 115 consists in combining the action of a pump with that of a turbine. The impeller combines the functions of pump impeller and turbine runner; the water which enters it under the initial head being discharged 120 from the admission chamber with a velocity so directed as to exert a forward turning moment or torque on the impeller similarly to the water discharged by the guide vanes of a turbine into the runner; the impeller 125 then operating upon this water as a pump. The torque which must be applied to the pump shaft is merely the difference between the torque imparted by the impeller to the leaving water and the torque exerted on 130

the impeller by the entering water. The pump can therefore operate with a low applied torque and consequently at high speed.

In order to realize the advantages of the above methods, it remains to reconvert the high velocity of discharge from the impeller, resulting from the measures described, into pressure head at the pump discharge, without undue losses of head. This 10 operation is provided for in the novel form of discharge casing which is an important feature of this invention.

In some of the following claims I employ the term "convergent helical path" to refer to the course followed by water approaching the impeller of my pump; that is, having the character of a curve traced by a point moving toward the center along a plane spiral, while the plane of the spiral 20 is moved in a direction perpendicular to the plane. From this explanation, the term "divergent helical path" will be obvious. (See also Fig. 1).

I claim:

- 25 1. In a rotary hydraulic pump, the combination of an impeller, means to deliver the water thereto under a considerable head and to convert the energy of that head into a high velocity of whirl of the entering water around the axis of the impeller, and means to deliver the water therefrom with a whirl in the same direction and to convert that whirl into static head on the outflow side of the pump.
- 30 2. In a rotary hydraulic pump, the combination of an inflow conduit adapted to deliver the supply water along convergent helical paths and with increasing velocity to the impeller, an impeller adapted to receive water with a high velocity whirl in the same direction as the rotation of the impeller and to deliver it with a high velocity whirl in the same direction, and an outflow conduit adapted to discharge water 45 along divergent helical paths with decreasing velocity.
- 35 3. In a rotary hydraulic pump, the combination of an impeller, a casing around the same, and a spiral conduit to receive the water from the impeller, said impeller casing opening into said spiral conduit by a diverging annular passage.
- 40 4. In a rotary hydraulic pump, an unshrouded axial flow impeller, in combination with a volute discharge conduit wrapped in a single turn around said impeller and having an annular passage thereto from the impeller, said annular passage being vane-free and bounded by surfaces of 50 revolution coaxial with the impeller.
- 45 5. In a rotary hydraulic pump, the combination of a high speed impeller adapted to pass a stream of water therethrough of comparatively small cross-section and at

high velocity, means to deliver the supply water to the impeller under considerable head and to utilize the same to move the water into the impeller at a proper high speed, and means on the outflow side of the pump to receive the water from the impeller 70 with high velocity energy and to convert the same into static head.

6. In a rotary hydraulic pump, the combination of an impeller, a casing around the same, a diverging annular conical passage 75 to receive the outflow water from the impeller and a spiral conduit having an annular opening connected to said passage and having a cross-section increasing around the axis at a rate greater than necessary to accommodate the increments of flow from said annular passage.

7. The method of moving a large volume of water against a moderate net head, which consists in placing a pump at a point where 85 it will receive the water from the supply source at a considerable head, converting that head into whirl energy, operating on the whirling water with a high speed impeller rotating in the same direction as the 90 whirl with low torque and thereby delivering the water from the impeller with a relatively small increase of its whirl energy, and converting the whirl energy of the delivered water into a static head greater than that of 95 the supply source.

8. The method of moving a large volume of water against a moderate net head, which consists in placing a pump at a point where it will receive the water from the supply 100 source at a considerable head, converting that head into kinetic energy whereby the water is delivered to the pump in a stream of comparatively high velocity, operating on this high velocity stream with a high speed 105 impeller at moderate torque and thereafter reconverting the kinetic energy of the stream from the pump into static head on the outflow side thereof.

9. A rotary hydraulic pump having in 110 combination a high speed impeller, an inflow conduit, and an outflow conduit, said conduits and the impeller being disposed so that the course of the water flowing through the pump shall be in a continuously advancing helical path first converging to its smallest cross section at or near the impeller and then diverging therefrom, the cross section at or near the impeller being such as to give a high velocity therethrough compared with 115 120 the velocity corresponding to the net head of the pump.

10. A rotary hydraulic pump for operating at a moderate net head having in combination a high speed impeller, an inflow 125 conduit, and an outflow conduit, said conduits and the impeller being disposed so that the course of the water flowing through

the pump shall be in a continuously advancing helical path first converging to its smallest cross section at or near the impeller and then diverging therefrom, said conduits being so formed that the cross sections of the stream elements across the lines of flow are less in accordance with nearness to the impeller.

11. A rotary hydraulic pump having in combination a high speed impeller, an inflow conduit adapted to convey the water to the impeller with a convergent whirling motion, an outflow conduit having a divergent helical course from the impeller about the impeller axis, and a free continuous annular space bounded by surfaces of revolution between said impeller and said outflow conduit.

12. A rotary hydraulic pump having in combination a high speed impeller, a driving shaft therefor, an inflow conduit around the axis of said shaft approaching convergently to the impeller, guide vanes in said inflow conduit, an annular outflow conduit around said shaft receding divergently from the impeller, a continuing outflow conduit around said annular outflow conduit, and a stay vane ring in said continuing outflow conduit, said guide vanes and said stay vane ring serving as mechanical supports for the parts of the structure.

13. A rotary hydraulic pump having in combination a high speed impeller, a driving shaft therefor, an inflow conduit around the axis of said shaft approaching convergently to the impeller, one set of stay vanes in said inflow conduit, an outflow conduit around said shaft receding divergently from the impeller, another set of stay vanes around said outflow conduit, and means transmitting a thrust through the one set of stay vanes to the other set of stay vanes.

14. A rotary hydraulic pump having in combination a high speed impeller, a conduit adapted to deliver the water thereto with a convergent whirl, and a conical annular diffuser to receive the water from the impeller.

15. In a rotary hydraulic machine, a rotary vane having two sections that serve as directrices, said sections being made by conical surfaces co-axial with the axis of rotation and being shaped to have different angles of inclination with respect to the tangential direction at the points of entrance and discharge of water, and said vane having its contour generated by a straight line contained in a revolving meridian plane and guided by said directrices.

16. In a rotary hydraulic machine, a rotary vane with modified helicoidal surfaces of non-uniform pitch, said surfaces being so characterized that each point of such surfaces is a point on a straight line element of

the surface, each of said elements being 65 transverse to the direction of flow through the impeller.

17. A rotary hydraulic pump having in combination an unshrouded impeller of substantially axial-flow type discharging into 70 an annular diffusion chamber coaxial therewith and having walls formed as surfaces of revolution generated by lines composed of elements oblique to the axis, and means for imparting whirl to the water entering said 75 impeller.

18. A rotary hydraulic pump having in combination an impeller of substantially axial-flow type, an admission chamber formed to deliver water to the impeller with 80 a large whirl component of velocity, a continuous annular discharge space bounded by surfaces of revolution co-axial with the impeller to receive the discharge therefrom, and a spiral conduit to receive the discharge 85 from the annular discharge space and formed to receive the water entering it in a direction having a considerable axial component.

19. A rotary hydraulic pump having in 90 combination a high speed impeller, an entrance conduit containing guide vanes formed to deliver the water to the impeller with a convergent whirl, a conical annular diffuser to receive the water from the impeller and a stay vane ring receiving the 95 discharge from the diffuser and containing vanes shaped to conform to the flow, the said guide vanes and stay vanes being capable of acting as stays or mechanical supports between the walls of the conduits.

20. In a rotary hydraulic pump, the combination of an impeller, means to deliver the water thereto under a considerable head and to convert the energy of that head into 105 a high velocity of whirl of the entering water around the axis of the impeller and a spiral conduit of expanding cross section to receive the water from the impeller with a whirl in the same direction and to reduce its velocity 110 so as to convert such whirl into static head on the outflow side of the pump.

21. In a rotary hydraulic pump, an axial flow impeller in combination with a discharge conduit and an enlarging annular 115 diffuser free of directing vanes leading from said impeller to said conduit.

22. In a rotary hydraulic pump, an unshrouded axial flow impeller, in combination with a volute discharge conduit wrapped 120 in a single turn around said impeller and having an annular diffuser free of directing vanes leading from said impeller to said conduit.

23. In a rotary hydraulic pump, the combination of an impeller, an entrance conduit having means to direct the water toward the impeller with a high velocity whirl in the

same direction therewith, and a spiral discharge conduit to receive the water from the impeller with a high velocity whirl and reduce and rectify its velocity, there being a space for free whirl within a peripheral boundary on each side of the impeller adjacent thereto.

24. The method of moving a large volume of water against a moderate net head which 10 consists in converting the head of the supply source into a high velocity convergent whirl, continuing such whirl freely within a peripheral boundary, applying an impeller to increase this whirl in a relatively moderate 15 degree, further continuing such whirl freely within a peripheral boundary, and then guiding the water away in a spiral course of expanding cross section with correspondingly reduced velocity.
- 20 25. In a rotary hydraulic pump, an axial flow impeller, in combination with a volute discharge conduit wrapped in a single turn around said impeller and having an annular chamber bounded by conoidal walls between 25 said impeller and said volute discharge conduit.

26. A rotary hydraulic pump having in combination an impeller of substantially axial-flow type discharging into an annular 30 diffusion chamber coaxial therewith and having walls formed as surfaces of revolutions generated by lines composed of elements oblique to the axis, and means for imparting whirl to the water entering said impeller.

- 35 27. A rotary hydraulic pump having in combination a high speed impeller, a driving shaft therefor, an inflow conduit around the axis of said shaft approaching convergently 40 to the impeller, a set of vanes in said inflow conduit, an outflow conduit around said shaft receding divergently from the impeller, and a set of vanes in said outflow conduit.

- 45 28. A rotary hydraulic pump for operating at moderate net head having in combination an impeller of high speed compared with the velocity corresponding to said head, a converging conduit adapted for acceleration 50 of the water on its way to the impeller, and a diverging conduit adapted to receive water from the impeller with a high velocity whirl in the same direction as the rotation of the impeller, and to decelerate said water 55 on its way from the impeller.

29. A rotary hydraulic pump for operating at moderate net head having in combination an impeller of high speed compared with the velocity corresponding to said head, 60 a converging spiral inflow conduit adapted for giving the water a high whirl velocity as it goes to the impeller, and a diverging spiral outflow conduit adapted for reconverting the high whirl velocity of the water

as it leaves the impeller and making it available as static head.

30. A rotary hydraulic pump for operating at moderate net head having in combination a high speed impeller compared with the velocity corresponding to said head, a 70 converging conduit adapted for acceleration of the water on its way to the impeller, and a diverging conduit adapted for deceleration of the water on its way from the impeller, the head on the inflow side of the 75 pump and the head on the outflow side of the pump each being great compared with the difference of said heads.

31. The method of moving a large volume of water against a moderate net head, which 80 consists in placing a pump at a point where it will receive the water from the supply source at a considerable head, converting that head into whirl energy, operating on the whirling water with an impeller rotating at a speed which is high compared with the velocity due to said net head, said impeller rotating in the same direction as the whirl with low torque and thereby delivering the water from the impeller with a relatively small increase of its whirl energy, 85 and converting the whirl energy of the delivered water into a static head greater than that of the supply source.

32. In a rotary hydraulic pump, an impeller of type of flow having a large component of axial flow but having a minor component of inward flow, in combination with a converging inflow conduit and a diverging outflow conduit.

33. In a rotary hydraulic pump, the combination of an impeller, an inflow conduit with decreasing cross-section across the flow lines and having guide vanes adapted to deliver the supply water along a convergent 105 helical path to the impeller with a high velocity whirl in the same direction as the rotation of the impeller, and an outflow conduit adapted to receive the water with a high velocity whirl in the same direction 110 and to conduct it along a divergent helical path with increasing cross-section across the flow lines.

34. In a rotary hydraulic pump, the combination of an impeller, a casing around the 115 same, and a spiral conduit to receive the water from the impeller, said impeller casing opening into said spiral conduit by an annular passage, said annular passage being vane-free and bounded by surfaces of revolution coaxial with the impeller.

35. In a rotary hydraulic machine, a rotary vane with modified helicoidal surfaces of non-uniform pitch, said surfaces being generated by a straight line lying always in 125 a revolving meridian plane and moving in that plane and making a varying angle with the axis as said plane revolves.

36. In a rotary hydraulic pump, an axial flow impeller in combination with a velocity reducing volute discharge conduit wrapped in a single turn around said impeller, and
5 an annular chamber bounded by conoidal walls between said impeller and said volute discharge conduit.
37. In a rotary hydraulic pump, an axial flow impeller in combination with a discharge conduit in the form of a spiral helical volute, and an annular chamber bounded by conoidal walls between said impeller and said volute discharge conduit. 10

LEWIS FERRY MOODY.
